[57] CLAIM

The ornamental design for a all purpose wash scrub polish and buff glove, as shown and described.

DESCRIPTION

FIG. 1 is a front elevational view of the all purpose wash scrub polish and buff glove showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an exploded elevational view thereof showing the separated pads from the rear.

The patterns shown on the pad portions of the claimed design in FIGS. 1 and 2, which are partially shown for ease of illustration, represent conventional materials and are understood to repeat throughout the areas indicated.

FIG. 1

FIG. 2

FIG. 3

FIG. 4

FIG. 5

FIG. 6

FIG. 7
